Des. 176,758
Patented Jan. 31, 1956

176,758

HEADREST

Sam Jones Edmonson, Burkeville, Va.

Application June 17, 1954, Serial No. 31,056

Term of patent 3½ years

(Cl. D3—9)

Fig. 1.

Fig. 2.

Fig. 3.

Fig. 4.

Figure 1 is a plan view of the improved head rest.

I claim:
The ornamental design for a head rest, as shown.
